UNITED STATES PATENT OFFICE.

EWALD F. PAWSAT, OF SHEBOYGAN, WISCONSIN, ASSIGNOR TO WALD MANUFACTURING COMPANY, OF SHEBOYGAN, WISCONSIN.

LUGGAGE CARRIER.

Application filed July 8, 1922. Serial No. 573,663.

To all whom it may concern:

Be it known that I, EWALD F. PAWSAT, a citizen of the United States, residing at Sheboygan, county of Sheboygan and State of Wisconsin, have invented new and useful Improvements in Luggage Carriers, of which the following is a specification.

This invention relates to improvements in luggage carriers of the type adapted to be clamped to a vehicle running board to retain articles of luggage thereon.

It is the object of this invention to produce a luggage carrier of the lazy tong type which can be easily and cheaply manufactured, and which will be readily operative and will fold compactly.

More particularly, it is the object of this invention to produce a luggage carrier having a body portion of the lazy tong type and standards for the ends of the carrier which can each be made economically from flat material and are nevertheless so shaped as to permit of a sliding and hinged connection to the body of the device.

In the drawings:

Fig. 1 is a side elevation of a luggage carrier embodying this invention as it appears applied to a vehicle running board.

Fig. 2 is a front end elevation of the same.

Fig. 3 is a detail view showing one of the end supports in rear elevation.

Fig. 4 is a detail view showing one of these supports in horizontal section taken on the line 4-4 of Figure 2 and illustrating the mode of attachment of the body of the luggage carrier thereto.

Fig. 5 is a view on a reduced scale illustrating the appearance of this improved luggage carrier when folded.

Like parts are identified by the same reference characters throughout the several views.

A vehicle running board or like supporting shelf is indicated at 10. Luggage carriers of the general type disclosed herein are well known and are commonly associated with vehicle running boards by being clamped to the outer margin thereof to keep parcels or luggage from falling from the board when placed thereon. It is ordinarily desired that such luggage carriers

shall be collapsible and that they may readily be extended to any desired length within a wide range at the time of attachment to the vehicle. In manufacturing a luggage carrier of this type, I prefer to use the well known lazy tong body shown at 11, wherein a plurality of bars 12 and 13 are pivotally connected intermediate of their ends by rivets or bolts 14, and at their ends by similar rivets 15 and 16, respectively. Obviously, the number of bars so connected may be multiplied indefinitely. The mode of construction of this type of luggage carrier body is well known and it is not thought to need further description.

Ordinarily, in addition to the end supports hereinafter to be described, the body 11 is provided with a central support for means of attachment to the running board 10. This central support is very simple and preferably comprises a U-shaped clamping element 18' with which a set screw 17 is in threaded engagement. This U-shaped element is riveted or otherwise secured to the member 18 which is connected to the luggage carrier body 11 intermediate of its ends by a rivet or bolt 16' similar to the rivets 16, but elongated for the purpose of securing to the body of the carrier the member 18. This central clamping device is preferably the same as the central clamp which has been fully disclosed in my pending application executed June 5, 1922.

At each end of the body 11 of the luggage carrier, is an upright 19 which provides support for the device. These uprights are preferably made from a single piece of scrap iron or a correspondingly formed strip of other metal. Intermediate the ends of the upright portion, its side margins 20 and 21 are bent rearwardly and brought together in the manner shown in Fig. 3, whereby the intermediate portion of the upright is made round in cross section. This fact is made clear in Fig. 4 wherein an intermediate portion of the upright 19 is shown in cross section. The upper extremity 22 of the upright is not rounded in this manner, but is allowed to remain flat as an anchorage for the bracing element 23 hereinafter to be described. Upon either side of the flat

upper extremity 22 of the upright are flanges 24 comprising upwardly bent margins of the original strip of metal which at 25 are brought together to form the rounded 5 intermediate portion above described. The flanges 24, bearing upon each side of the bracing element 23, contribute materially to the rigidity of the structure.

At the lower end of upright 19, an integral and channelled L-shaped member 27 is formed. The margins 20 and 21 of the original strip of material are parted at 28 and bent sharply outwardly to form the shoulders 29 and 30. Thereafter these 15 margins are made to comprise marginal flanges 31 and 32 from either side of the flat portions 33 and 34 which constitute the two legs of the L-shaped element 27. It will be understood that the entire structure 20 illustrated in Fig. 3 including the flat, upper extremity 22 and rounded body portion of the upright 19, together with the channelled, L-shaped element 27 at the lower end of the upright, is made of a single strip 25 of metal bent to the desired shape by a simple process. The resulting structure is at once light and strong, being reenforced throughout its length either by the rolled intermediate portion or by the flanges at either end.

30 For the purpose of clamping the uprights to the running board 10, I provide a U-shaped clamp 35 having one elongated arm 36 adapted to rest upon the upper surface of the running board. The shorter arm 37 of the clamp is provided with a clamping bolt or set screw 38 arranged to engage the lower side of the running board. The two arms 36 and 37 are so spaced apart by the intermediate portion 38' of the clamp as to 35 fit closely between the shoulders 29 and 30 of the upright and the lower leg 34 of the L-shaped element at the end thereof. The intermediate portion 38' of the clamp is secured by a rivet or bolt 39 to the upper leg 33 of the L-shaped element 27 and is confined between the flanges 31 and 32 of the upper leg. The arm 37 of the clamp contacts with the lower leg 34 of the L-shaped element and is similarly confined by the 40 marginal flanges 31 and 32 thereof. As previously stated, the clamp is secured against upward movement relative to the upright by the fact that it abuts against shoulders 29 and 30 thereof.

55 A brace 23 is preferably secured by a rivet or other desired securing means to the extremity of the elongated arm 36 of the clamp and extends upwardly and then horizontally to the upper extremity 22 of the upright to which it is secured by a rivet 40 or like means. The brace 23 may, in turn, be braced or made rigid by an intermediate brace 41 attached thereto and to the arm 36 of the clamp in the manner 60 clearly shown in Fig. 2.

It will be obvious from a scrutiny of Fig. 2 that the end support for the body 11 of the luggage carrier is an extremely stable structure. The relation of the upright 19, bracket 35 and brace 23 to each other is such 70 that each of these elements cooperates with each of the other elements to provide a rigid and strong support with a correspondingly secure mounting upon the running board. The clamp 35 is reenforced against the spreading of its arms 36 and 37 by the peculiar structure of the upright 19 and brace 23. Similarly the upright is strengthened by its association with the clamp and the brace, and the brace, in turn, is rendered 75 more serviceable in its function of securing luggage against longitudinal movement upon the running board by means of its peculiar mounting at the upper end of the upright and by means of the adequate reenforcement given it by the clamp.

80 For attaching the body 11 of the luggage carrier to the uprights at either end thereof, I prefer to use an integral collar and link unit, such as is shown at 41 in Figs. 1 and 4. Similar units are used to secure the free ends of each of the bars 12 and 13 at the ends of the body 11. Each unit includes a pair of spaced arms 42 and 43 connected adjacent their ends by a rivet or bolt 44. Between said arms an integral portion of the unit is bent to form an annulus or collar 45 of a size adapted to receive the intermediate rounded portions of the uprights 19. The axis of the collar or annulus 45 is preferably disposed wholly at one side of arms 42 and 43 in the manner clearly shown in Fig. 4 in order to facilitate the folding of the luggage carrier for 85 storage.

90 None of the collars 45 are secured against axial movement upon the rounded portions of their respective uprights 19. Due, however, to the fact that the rivets 44 are located at a considerable distance from the axis of the collars, a considerable moment is developed which tends to cause the collars to bind upon the uprights upon some occasions. To the end, therefore, that this binding may not interfere with the ready opening and closing of the luggage carrier, I prefer to provide in the upper extremities of the bars 12 and 13 at the ends of the carrier body, elongated slots 46 through which 95 pass the rivets or pins 44 which connect arms 42 and 43 of the link and collar units 41. A sliding and pivotal connection is thereby established which allows the bars 12 and 13 of the entire body 11 of the carrier to move naturally and freely when the carrier body is opened and closed.

100 To operate the luggage carrier, the body portion will first be expanded to the position in which it is shown in Fig. 1. The upper extremities of the links 12 and 13 at 105

the end of the body portion will slide upon the pins 44 and will pivot about said pins sufficiently to assume their angular position as shown. Similarly, in collapsing the body portions, the upper extremities of these bars will have their pivotal and sliding movement on pins 44.

With the body of the device collapsed, the end structures, including the upright 19, 10 clamp 35, and the bracing elements 23 and 41, may be folded over the body in the manner shown in Fig. 5. This folding operation is facilitated by the fact that the collar 45 which comprises a part of the attaching unit 41 is offset from the remainder of the unit, thereby positioning the entire body at the outside of the end structure and enabling these structures to be folded inwardly against the body. The folding operation is further facilitated by the fact that the collars 45 are unsecured upon the rounded intermediate portions of uprights 19 and by the fact that said intermediate portions are rounded for a distance greater than the maximum separation of the two collars 45 at each end of the device. Thus, even with these collars at their maximum separation, it is possible to slide either of the upright structures axially through the set of collars 30 threaded thereon and thereby to displace one of the end structures relative to the other in a manner enabling them to be folded together without interference in the manner shown in Fig. 5. This particular device is best folded by extending the bracing elements 23 and elongated clamp arms 36 of one end structure between the corresponding members of the other structure, as shown.

40 I claim:

In a luggage carrier provided with a collapsible lazy tong body composed of pivotally connected bars, an upright provided with flat portions adjacent its extremities and tubularly rounded intermediate said flat portions, a collar threaded upon the tubularly rounded intermediate part of the upright, arms projecting laterally from the collar and spaced apart to receive one of said bars, and a pin connecting said arms, the bar received between said arms being slotted to receive the pin.

2. In a luggage carrier provided with a collapsible lazy tong body including a plurality of pivotally connected bars, an end support comprising an upright provided with flat portions adjacent its end and with an intermediate tubular portion, a pair of collars threaded upon said tubular portion, spaced arms projecting laterally from said collars and adapted to receive between them the free ends of bars of the body, and pins connecting the spaced arms of each collar, one of the body bars being apertured to receive one of said pins and another of the

body bars being slotted to receive the other of said pins.

3. A luggage carrier end structure including an upright provided with an intermediate portion bent to tubular form, a flanged flat element at the upper extremity of the upright, a marginally flanged attaching member associated with the lower extremity of the upright, a U-shaped clamping device provided with an elongated arm and disposed within said attaching member confined between the marginal flanges thereof, means for securing the clamping device to the attaching member at a single point and adapted to cooperate with said marginal flanges in rigidly positioning the attaching member relative to the clamping device, and a brace connecting the elongated arm of the clamping device with the flat element at the upper extremity of the upright and confined between the flanges of said element.

4. A luggage carrier including a collapsible lazy tong body provided at its ends with apertured bars, uprights at the ends of the body comprising flat pieces of metal having intermediate portions of their margins bent arcuately in transverse section, whereby to provide intermediate rounded portions and flat extremities, clamping devices adapted to engage a vehicle running board and secured respectively to the said extremities of said uprights, collar and link units slidably and rotatably associated with the uprights and pivotally connected to the apertured bars at the bottom of the body, and similar units slidably and rotatably associated with the uprights and pivotally and slidably connected with others of the apertured bars at the upper end of the body.

5. A luggage carrier including a lazy tong body composed of pivotally connected bars, the free extremities of certain of said bars being apertured, uprights comprising strips having intermediate portions of their margins bent arcuately in transverse section, whereby to provide intermediate rounded portions and relatively flat terminal extremities, collar and link units slidably and rotatably mounted on the uprights and pivotally connected with the apertured extremities of bars at the bottom of said body, similar collar and link units slidably and rotatably mounted upon the uprights adjacent the top of the body and pivotally and slidably connected to apertured bars thereof, said collar and link units being formed to offset the body laterally of said uprights, whereby said uprights are foldable on the body, and bracket means secured to the relatively flat extremities of said uprights and adapted to engage a running board.

6. A luggage carrier end structure including an upright comprising an elongated strip of metal with the margins of the intermediate portions bent inwardly and brought

together in tubular form, an integral foot at the lower extremity of said upright disposed at right angles thereto and provided with marginal flanges, and corresponding flanges formed on said upright adjacent said foot.

7. A luggage carrier end structure includ-

ing an upright comprising an elongated strip of metal with the margins of the intermediate portions bent inwardly and brought together in tubular form, an integral foot at the lower extremity of said upright and disposed at right angles thereto.

EWALD F. PAWSAT.
